LET-OFF MECHANISM FOR LOOMS

Arthur Grenier, Lawrence, Mass.

Application July 31, 1937, Serial No. 156,804

2 Claims. (Cl. 188—83)

My invention relates to improvements in let-off mechanism for looms and the primary object thereof is the provision of an efficient, simply constructed and inexpensive mechanism for imposing braking tension in variable degree against the warp beam of a loom and within a wider range of variation than can be accomplished with present day mechanisms of this character.

The invention also comprehends other objects, subordinate in character, all of which together with the precise nature of my improvements will be readily understood when the following description and claims are read with reference to the drawings accompanying and forming part of this specification.

In said drawings:—

Figure 1 is a fragmentary view in side elevation of a portion of a loom equipped with my improved let-off mechanism.

Figure 2 is a fragmentary view in perspective of one end of a lever forming part of the said mechanism.

Figure 3 is a view in top plan of a link forming an extension for said lever.

Figure 4 is a view in side elevation of said link, and

Figure 5 is an end elevation of the link.

Referring to the drawings by numerals, my invention has been shown as applied to a portion of a loom having duplicate side frame members one of which is shown at 1, and the usual warp beam 2 rotatably mounted by trunnions, as at 3, in bearings, as at 4, on a stepped down portion 5 of each frame member 1.

The let-off mechanism includes a brake band 6 surrounding one end of said beam 2 for frictional engagement therewith and having a fixed end 7 secured to the upper edge of the adjacent frame member 1 by a stud 8, and also having a free end adapted to be upwardly tensioned in variable degree to frictionally retard rotation of said beam 2 in opposition to the pull exerted thereagainst by the pay-off of the warp thread thereon and not shown. The free end 9 of said band 6 is tensioned by means including a horizontally disposed lever 10 fulcrumed adjacent one of its ends on the upper edge 11 of the frame member 1 above said band 6 and beam 2 and by means of a lug 12 on the lower edge thereof seating in a socket 13 provided in said frame member 1. The fulcrumed end of the lever 10 is provided with a series of notches in its upper edge beyond the lug 12 and as shown at 14. The free end 9 of the brake band 6 is connected to the fulcrumed end of the lever 10 by means of a

vertically disposed bolt 15 having a stud 16 at its lower end to which said free end of the brake band 6 is suitably secured, said bolt having a hanger member 17 slidably mounted on its upper end and adapted to seat in selected notches 14. The fulcrumed end of the lever 10 may be bifurcated as shown at 14' to receive the bolt 15 therebetween. A nut 18 threaded on to the upper end of the bolt 15 provides for adjusting the free end of the brake band 6 relative to the fulcrumed end of the lever 10 for a purpose presently seen. The other end of the lever 10 overhangs the band 6 and has a free downwardly curved end 19 terminating in a straight portion 20. The straight portion 20 has a plurality of notches 21 formed in the upper edge thereof and spaced longitudinally along said edge.

Removably mounted on the free end 19 of the lever 10 is a link 22 forming an extension of said end. The link 22 comprises a looped end 23, a hook shaped end 24, and a pair of transverse bars 25 extending across the looped end and spaced apart to correspond with the spacing of the notches 21. The looped end 23 straddles the free end 19 of said lever 10 and bears upwardly against the under edge thereof, the bars 25 seating in the notches 21. A second link 26 is hooked over the hooked end 24 of the link 22. A weight 27 is secured in any suitable manner to said links 26.

Referring to the operation, by locating the hanger 17 in different notches 14 the tension on the brake band 6 may be varied from the fulcrumed end of the lever as will be understood. Also tension at this end of the lever may be varied by manipulation of the nut 18. The link 22 may be removed and the weight supporting link 26 suspended from the free end of the lever 10 by location in selected notches 21 thereby varying the tension at the free end of the lever 10. Thus it will be seen that the link 22 and the means for mounting the same on the lever 6 provide a very simple means for optionally varying at will the tension of the brake band 6 and supplementing the means at the other end of said lever 10.

My invention will, it is believed, be understood from the foregoing description thereof without further explanation.

Manifestly the invention, as described, is susceptible of modification without departing from the inventive concept and right is herein reserved to such modifications falling within the scope of the claims appended hereto.

What I claim is:—

1. The combination with a rotatable warp

beam, of let-off mechanism for controlling rotation thereof comprising a brake band surrounding said beam for frictional engagement therewith and adapted for variable tensioning against said beam, and means for variably tensioning said band including a horizontally disposed fulcrumed lever having a free downwardly curved end provided with notches in the upper edge thereof, a link removably mounted on said free end to form an extension thereof and provided with cross bars seating in said notches and a looped end straddling the free end of said lever and bearing against the under edge thereof, and a weight suspended from the other end of said link.

2. The combination with a rotatable warp beam, of let-off mechanism for controlling rotation thereof comprising a brake band surround-

ing said beam for frictional engagement therewith and adapted for variable tensioning against said beam, and means for variably tensioning said band including a horizontally disposed fulcrumed lever having a free downwardly curved end provided with notches in the upper edge thereof, a link removably mounted on said free end to form an extension thereof and comprising a looped end and a hook shaped end, said link having cross bars in the looped end thereof seating in said notches and said looped end straddling said free end of the lever and bearing against the under edge thereof, a second link suspended from the hooked shaped end of the first mentioned link, and a weight secured to said second mentioned link.

ARTHUR GRENIER.
